RECLOSABLE POURING OPENING FOR CONTAINERS

Frank D. Bergstein, Hamilton, Ohio, assignor to Bergstein Packaging Trust, a trust composed of Robert M. Bergstein and Frank D. Bergstein, trustees

Application October 12, 1956, Serial No. 615,585

13 Claims. (Cl. 229—17)

This is a continuation-in-part of my copending application, Serial No. 415,030, filed March 9, 1954, now abandoned.

My invention relates to containers which are particularly suited for liquids or other materials requiring a sealed condition of the container, and relates specifically to an improved reclosable pouring opening for such containers.

In my Patent 2,549,048, dated April 17, 1951, and entitled Liquid-Tight Carton and Method, I have disclosed the provision of a liquid-tight carton in which the carton ends are sealed by interior end flooding, the carton being provided across the inner surfaces of its end closures with relatively thick castings of sealing substance which bond to the end closures and to the adjacent ends of the carton body walls to provide a completely sealed structure. In accordance with the teachings of the patent, one of the end closures may be provided with a dispensing or pouring opening extending therethrough, the opening being covered by a liftable flap member lying to the outside of the end closure. When the interior end casting is formed the sealing substance will fill the pouring opening and bond to the inner surface of the liftable flap; and the subsequent lifting of the flap member will result in the fracturing of the casting along a line determined by the periphery of the pouring opening, thus providing a plug-like element formed from the casting and bonded to the liftable flap member. The closure plug so formed may be readily reinserted in the pouring opening to reseal the carton.

The thickness of the closure plug is determined by the thickness of the several closure flaps through which the pouring opening is formed plus the thickness of the interior end casting. Since the pouring opening was formed through a plurality of flaps and the end casting was of substantial thickness, the resultant plug was of ample thickness to effectively reseal the carton. However, I have now found that it is desirable in many instances to confine the pouring opening to a single flap member; but where this is done, the effective thickness of the plug-like element formed on the liftable flap is reduced to the extent that it is no longer effective to tightly seal the container upon re-entry into the pouring opening. For example, where the pouring opening is formed through three layers of .020 boxboard plus the adhesive layers between them, there is a thickness of more than 60 thousandths or approximately $\frac{1}{16}$ of an inch of sealing material in the pouring opening. In a single ply closure this is reduced by more than $\frac{2}{3}$ or to about $\frac{1}{50}$ of an inch, which is insufficient for a dependable closure. Similarly, I have found other instances wherein it is desirable to reduce the thickness of the end casting or for that matter to eliminate it entirely. The positive pressure sealing of present day containers eliminates the need for interior end sealing for some uses, and in these instances the sealing substance will be confined to the pouring opening where it will form a reclosure plug. In accordance with the instant invention, I have provided a construction wherein the

pouring opening may be confined to a single end closure flap and yet, due to the flared configuration of the opening, the thickness of the closure plug formed therein will be materially increased even though the thickness of the end casting is reduced to a minimum or eliminated entirely.

It is, therefore, a principal object of my invention to provide a reclosable container having a pouring opening formed therein which has an effective thickness which is substantially greater than the thickness of the closure member in which the opening is formed.

It is a further object of my invention to provide a reclosable container of the character described having a flared or flanged pouring opening which defines, in effect, a well or cavity into which sealing material or the like may be introduced to form a plug-like closure element of desired thickness.

These and other objects of my invention which will appear hereinafter or which will be apparent to the skilled worker in the art upon reading these specifications, I accomplish by that construction and arrangement of parts of which I shall now describe certain exemplary embodiments.

Reference is now made to the accompanying drawings which form a part hereof and in which:

Figure 1 is a plan view of a carton blank having the pouring opening confined to a single closure flap.

Figure 2 is a sectional view taken along the line 2—2 of Figure 1.

Figure 3 is a partial perspective view showing the top of the tubed and erected blank prior to infolding of the closure flaps.

Figure 4 is a perspective view of the container with the top closure flaps in closed condition.

Figure 5 is a perspective view similar to Figure 4 but with the container in inverted position.

Figure 6 is a partial vertical sectional view taken along the line 6—6 of Figure 5.

Figure 7 is a partial vertical sectional view similar to Figure 6.

Figure 8 is a perspective view of a completed container with the liftable flap member in raised position.

Figure 9 is a vertical sectional view taken along the line 9—9 of Figure 8.

Figure 10 is a sectional view similar to Figure 8 illustrating a modified form of the invention.

Figure 11 is a partial perspective view illustrating an alternative form of carton construction.

Referring now to Figure 1 of the drawings, I have therein illustrated a blank for an exemplary carton having a series of body walls 1, 2, 3 and 4 in articulation, with a glue flap 5 articulated to the free edge of the wall 4. Closure flaps 6, 7, 8 and 9 are provided at the tops of the body walls. In the embodiment illustrated the flap 6 is an enlarged flap and has formed therein a liftable flap portion 10 having extending flanges 11 and 12. Flap 7 is also an enlarged flap and it is provided with a pouring opening 13 arranged to register with the liftable flap 10 in the erected structure. The flaps 8 and 9, on the other hand, are narrow flaps which are adapted to be folded outwardly and secured in face-to-face contact with the extending edges of the enlarged flaps 6 and 7, as will become apparent hereinafter.

The body walls 1 through 4 of the container shown in Figure 1 will be provided at their bottom ends with suitable bottom closure flaps 14, 15, 16 and 17. The arrangement of the flaps is such that they may be nested top closure to top closure and bottom closure to bottom closure in a continuous web, thereby effecting a substantial saving in material.

The container will be preferably made from paperboard suitably proofed in view of the nature of the liquid

which is to be placed in it. The character of the proofing does not, however, form a specific limitation upon this invention and the proofing may be accomplished in any of the ways known to the skilled worker in the art.

In accordance with the instant invention, the pouring opening 13 is flared or flanged about its periphery so as to effectively increase the thickness of the pouring opening beyond the thickness of the flap in which it is formed. As best seen in Figure 2 of the drawings, the pouring opening is formed with a flared or flanged edge 18 which defines a well 19 for the reception of the sealing substance. Preferably, the pouring opening will be flared upwardly toward the outermost closure flap in the manner illustrated in Figures 2 and 3, although as will be pointed out hereinafter, the opening may be flared downwardly, i.e. in the opposite direction, without departing from the spirit of the invention.

The container blank of Figure 1 will be tubed in the ordinary way through the use of conventional carton folding and gluing equipment. Where the container is to hold liquids, I prefer to tube it with the glue flap 5 lapped outside the free edge of the body wall 1, thereby juxtaposing the free side edge of body wall 1 to a corner of the carton. The longitudinal seam so formed may be then proofed by means of a continuous bead of sealing substance extending along the corner of the container in accordance with the teachings of my copending application Serial No. 331,441, filed January 15, 1953 and entitled Carton Sealed By Internal End Flooding, now Patent 2,754,044, dated July 10, 1956.

As will be evident from Figure 3, the top closure is formed by outfolding the narrow flaps 8 and 9, whereupon adhesive, indicated by the shaded areas, is applied to the outfolded flaps and the flap 7 folded to overlie the top end of the container. The flap 7 is of a size such that marginal edge portions thereof will overlie the narrow flaps 8 and 9 and will bond thereto in face-to-face relationship. A marginal stripe of adhesive 20 will be applied to the upper surface of flap 7, whereupon the closure flap 6 will be infolded to overlie the flap 7 to complete the end closure. The adhesive stripe 20 is so arranged that the liftable flap member 10 will be free from attachment to the underlying closure flap; and I have found it desirable to provide a diagonal strip of adhesive 21 on the under surface of the flap 6 in the area just beyond the liftable flap portion. The closed and sealed condition of the top closure is shown in Figure 4, it being understood that in the condition illustrated the liftable flap member 10 overlies and covers the flanged or flared pouring opening 18.

Subsequent to the formation of a top closure, the container may be inverted to the position illustrated in Figure 5, whereupon the desired quantity of sealing substance will be introduced into the container through the open end thereof. This may be conveniently done by means of a nozzle 22 (Figure 6) inserted in the container. The quantity of sealing material introduced through the nozzle will depend upon the type of closure being formed. If the sealing material is to be confined to the well 19 so as to form a closure plug bonded to the liftable flap 10, the nozzle 22 may be centered over the pouring opening as illustrated in Figure 6, whereupon an increment of sealing material forming a plug 23 will be deposited into the pouring opening. Of course, if an end casting is to be formed in addition to the closure plug, the sealing substance will be supplied in a quantity sufficient to form an imperforate seal of the desired thickness across the entire end of the container.

It is also within the scope of my invention to form the closure plug and end casting from different materials. This is illustrated in Figure 7 wherein the plug portion 24 is formed from a first material and the end casting 25 from a different material introduced in the container through a second nozzle 22a. The use of different materials enables me to impart special characteristics to the

plug which would be of no particular advantage in the end casting, or vice versa. For example, there are instances in which it will be desirable to form the plug portion from a relatively hard resinous material which will stand considerable abuse, whereas the end casting will be formed from a material which is resilient and capable of adhering tenaciously to the board from which the container is formed.

The nature of the sealing substance or substances employed does not constitute a limitation upon my invention. Furthermore, the term "sealing substance" as used herein denotes both plug forming materials and materials for forming the end castings. I prefer to employ a sealing substance which is thermoplastic in character and non-brittle when set. By reason of its brittleness, paraffin is not ordinarily advantageous as such, although mixtures of this wax with non-brittle microcrystalline waxes or the latter alone will serve. In some instances, however, ordinary paraffin will serve as a plug forming substance. Excellent results are obtained by using microcrystalline wax with or without paraffin but with the addition of resinous substances such as polybutenes, chlorinated terphenyls and others, which act to impart resilience and strength and increased bond, while still permitting the parting of the casting if such is required. The sealing material will be introduced in a relatively thin and liquid condition; and where an end casting is formed, I have found it of assistance in distributing the material to rock or tilt the container prior to the solidification of the sealing substance. Warming the end of the container will also assist the sealing substance in penetrating all orifices and interstices in the container to form an imperforate seal.

It will be understood that the container will also be closed upon its bottom end by interfolding and adhesively securing the flaps 14, 15, 16 and 17. This may be done in the usual way and with the usual apparatus while the carton is in the position illustrated in Figure 5. The manner in which the container is sealed does not constitute a limitation on my invention and the procedures taught in my copending application Serial No. 414,558, filed March 8, 1954 and entitled Containers Having Strong End Closures and Method of Making Them may be employed.

Upon being uprighted, the container may be opened by lifting the flap member 10, as shown in Figure 8. This will be done after the sealing material has solidified, but in the case of an end casting it is immaterial whether the casting shall have reached a particular stage of hardness. The lifting of the flap member 10 results in the opening up of a pouring opening defined by the flanged periphery 18 of the pouring opening, the sealing material occupying the well 19 coming out as a plug 26 in adhesive union with the raised flap 10. The container may be reclosed by folding flap 10 to its original position in which the plug 26 enters the flanged pouring opening to form an effective reclosure.

Figure 9 illustrates an end closure incorporating an outwardly flared pouring opening and an end casting covering the entire end of the container. Where the opening is flared outwardly, the plug 27 will be of a thickness substantially equal to the depth of the flared opening plus the thickness of the casting 28 at the sides of the opening. While the flared opening 18 is generally frustoconical when viewed in section, as in Figure 9, I have found that the plug 27 when it is broken away will have generally vertical walls, as illustrated. This results in a sealing material-to-sealing material contact throughout the depth of the plug which I have found to be highly desirable for a liquid-tight reclosure. The closure may be readily resealed by applying sufficient heat to the ends of the container to cause edge portions of the plug 27 to interfuse and join with edge portions of the casting 28. It can be pointed out also that upon reclosure the flared or flanged edge of the

opening will be flattened to some extent, thus tending to exert a gripping action on the plug.

While I prefer to direct the flared or flanged portion 13 upwardly or outwardly in the direction of the liftable flap member 10, it is also within the spirit of my invention to turn the flared or flanged portion downwardly or inwardly in the manner illustrated in Figure 10. As therein illustrated, the peripheral flange 18a extends in the direction of the internal end casting 28a, but this nevertheless results in the formation of a well 19a which will receive the filling substance and provide a plug of the desired thickness and of generally frustoconical configuration, such plug being indicated at 27a. It will be evident that the well 29a may be used to provide a plug analogous to the plug 23 illustrated in Figure 6, the sealing material being limited to the confines of the well.

It will be apparent from the foregoing description that the provision of a flared or flanged pouring opening results in the definition of a plug having a thickness considerably greater than the thickness of the flap in which the pouring opening is formed, thereby eliminating the necessity of providing a pouring opening defined in a plurality of flaps, as was required in the teachings of my aforementioned patent. In particular, the outwardly flared construction of Figure 9 enables me to provide a plug and end casting which results in a tighter and more perfect closure than is otherwise obtainable.

It will be understood that upon completion of the end closures and the formation of the closure plug, the container is in condition to be filled with the desired liquid contents. Such contents are introduced through the filling opening, and when the container has been filled to the desired level the flap 10 is folded to the closed position followed by the folding or crimping of the flanges 11 and 12 about the extending lip defined by the narrow flaps 8 and 9 and the extending edges of closure flap 7. As already indicated, heat may be supplied to the end closure to fuse the closure plug in the closed position.

While in Figure 6, I have illustrated the introduction of the sealing material into the well 18 by means of a nozzle inserted into the container body, it is also within the spirit of my invention to form the plug 23 prior to the erection of the container body walls or else as an incident of the formation of the top closure. To this end it is desirable to articulate the closure flap 7a to a side edge of the closure flap 6, as seen in Figure 11, the upper edge of the body wall 2 being provided with a narrow outfolded flap 7b. With this arrangement, it will be evident that the flap 7a may be folded and juxtaposed to the flap 6 with the interposition of adhesive therebetween, such as the adhesive area 21, thereby juxtaposing the flared pouring opening 18 to the under surface of the liftable flap member 10.

With the flap arrangement just described, it will be evident that the flap 7a may be juxtaposed to the flap 6 and secured while the remainder of the blank is in the condition illustrated in Figure 1, whereupon the increment of sealing substance may be introduced into the well 18 and permitted to solidify, whereupon the blank may be tubed and subsequently erected and sealed. Alternatively, the container blank may be first tubed and erected to the position of Figure 11, whereupon the two flaps may be juxtaposed and held in a horizontally disposed position with the flap 7a uppermost, whereupon the sealing substance may be introduced into the well and the plug cast in situ against the under surface of the liftable flap portion 10.

Additional modifications may be made in my invention without departing from the spirit of it. For example, while I have described my invention in connection with a flared or flanged pouring opening as would be formed by embossing or forming the paperboard in a die, the flared pouring opening could be formed by means of a series of spaced apart radially disposed slits which,

when displaced from the plane of the closure flap, will define a well of the desired thickness.

Having thus described my invention in several exemplary embodiments, what I desire to secure and protect by Letters Patent is:

1. A container having an end closure comprising a single thickness full width closure flap perforated to provide a dispensing opening, and an imperforate liftable flap member overlying and covering said perforation, said full width flap being flared about the periphery of said perforation to define a well having a depth in excess of the thickness of the end closure flap in which said perforation is formed, and a casting of sealing substance filling said well and contacting that portion of said liftable flap member uncovered by said perforation, whereby when said liftable flap member is raised, said casting will break away from said flared opening to form a plug having a thickness in excess of the initial thickness of said full width closure flap, thereby providing a plug portion adapted to reenter said flared opening to provide a tight seal for said pouring opening.

2. A method of providing a reclosable plug for a dispensing container having an end closure comprising a single thickness full width closure flap perforated to provide a dispensing opening and an imperforate liftable flap member overlying and covering said opening, which comprises the steps of flaring said full width closure flap about the periphery of said opening to define a well having a thickness substantially in excess of the thickness of the closure flap in which said opening is formed, and depositing in the well so formed a measured increment of sealing substance sufficient to fill said well and permitting said sealing substance to solidify in situ so as to provide a closure plug bonded to said liftable flap portion.

3. The method claimed in claim 2 wherein said pouring opening is flared in the direction of said liftable flap member.

4. The method claimed in claim 2 wherein the said pouring opening is flared in the direction opposite said liftable flap member.

5. The method claimed in claim 2 wherein the increment of sealing substance introduced into said well is a part of an end casting covering the entire exposed inner surface of said full width flap member.

6. A dispensing container having an end closure comprising a single thickness full width closure flap having a perforation therein, a liftable flap overlying said full width flap and the perforation therein, said full width flap being flared about the periphery of said perforation in the direction of said liftable flap so as to define a well of substantial thickness, and a casting of sealing substance filling said well and bonded to the portion of said liftable flap exposed by said perforation, whereby to provide a plug of sealing substance bonded to the said liftable flap and capable of being withdrawn from said perforation when said liftable flap is raised and reinserted therein when said liftable flap is lowered.

7. In a reclosable container having an end closure comprising a single thickness full width closure flap perforated to provide a dispensing opening, a liftable flap member overlying and covering said opening, said full width flap being flared about the periphery of said opening to define a well having a depth in excess of the thickness of said full width closure flap and closed at its bottom by said liftable flap member, and a casting of sealing substance on the interior surface of said full width closure flap, said liftable flap member in lifted condition having a plug of sealing substance formed thereon broken away from said casting and defined by said well, said plug having a thickness equal to the combined thickness of said well and said casting and adapted to be fitted into said well to reclose said container.

8. In a carton wherein a wall having a perforation therein is covered by an imperforate flap overlying said

perforation, and wherein a casting of sealing substance covers said wall interiorly, and also that portion of the flap uncovered by said perforation, so that when said flap is raised, a portion of the casting substantially outlined by the periphery of said perforation will break away from the remainder of the casting to form a plug having a thickness equal to the combined thickness of the remainder of the casting and the thickness of the wall in which said perforation is formed, the improvement which consists in flaring the said wall in the area surrounding said perforation to define a well closed at its bottom by the said liftable flap member, whereby the well so formed may be filled with sealing substance to effectively increase the thickness of said plug without increasing the thickness of the end casting or the thickness of the said wall.

9. A container having an end closure comprising a single thickness full width closure flap perforated to provide a dispensing opening, an imperforate liftable flap member overlying and covering said perforation, said full width flap being flared about the periphery of said perforation to define a well having a depth in excess of the thickness of the end closure flap in which said perforation is formed, and an interior casting of sealing substance covering said full width flap interiorly, filling said well and contacting that portion of said liftable flap member uncovered by said perforation, so that when said liftable flap member is raised, a portion of the casting substantially outlined by the periphery of said flared opening will break away from the remainder of said casting to form a plug having a thickness in excess of the combined thickness of the remainder of the casting and the said closure flap, whereby the thickness of the end casting may be maintained at a minimum for proofing the interior of the container and yet the plug portion will be of sufficiently increased thickness to provide a tight reseal upon being inserted in said flared opening.

10. A container having an end closure comprising a single thickness full width closure flap perforated to provide a dispensing opening, an imperforate liftable flap member overlying and covering said perforation, said full width flap being flared outwardly in the direction of said liftable flap member to define a well about the periphery of said perforation in excess of the thickness of the closure flap in which said closure flap is formed, and an interior casting of sealing substance covering said full width flap interiorly, filling said well and contacting that portion of said liftable flap member uncovered by said perforation, so that when said liftable flap member is raised, a portion of said casting substantially outlined by the periphery of said dispensing opening will break away from the remainder of said casting to form a plug having a thickness in excess of the combined thickness of the remainder of the casting and the full width closure flap, whereby the thickness of the end casting may be maintained at a minimum for proofing the interior of the container and yet the plug portion will be of sufficiently increased thickness to provide a tight reseal upon being reinserted in said flared perforation.

11. A container having an end closure comprising a single thickness full width closure flap perforated to provide a dispensing opening, and imperforate liftable flap member overlying and covering said perforation, said

5 full width flap being flared inwardly about the periphery of said perforation to define a well having a depth in excess of the thickness of the end closure flap in which said perforation is formed, and an interior casting of sealing substance covering said full width flap interiorly, filling said well and contacting that portion of said liftable flap member uncovered by said perforation, so that when said liftable flap member is raised, a portion of the casting substantially outlined by the periphery of said flared opening will break away from the remainder of said casting to form a plug having a thickness in excess of the combined thickness of the remainder of the casting and the thickness of the full width closure flap, whereby the thickness of the end casting may be maintained at a minimum for proofing the interior of the container and yet the plug portion will be of sufficiently increased thickness to provide a tight reseal upon being inserted in the said flared perforation.

12. A method of forming a reclosable plug on the 20 liftable flap portion of a dispensing container which comprises providing a dispensing end closure having a first closure flap with a dispensing opening therein, and a second closure flap having a liftable flap portion, flaring said first named closure flap about the periphery of said dispensing opening, juxtaposing said two closure flaps with the liftable flap portion of said second named closure flap overlying said dispensing opening, said flared dispensing opening defining a well closed at its bottom by said liftable flap portion, and introducing into the well 25 so formed a quantity of liquid sealing substance sufficient to substantially fill said well and bond to the exposed surface of said liftable flap portion, and permitting said liquid sealing substance to harden in situ, thereby providing a closure plug of substantial thickness and mating 30 exactly with the periphery of said dispensing opening.

13. A method of providing a reclosable plug for a dispensing container having an end closure comprising a single thickness full width closure flap perforated to provide a dispensing opening and an imperforate liftable flap member overlying and covering said opening, which 40 comprises the steps of flaring said full width closure flap about the periphery of said opening to define a well having a thickness substantially in excess of the thickness of the closure flap in which the opening is formed, and forming in said well a casting of sealing substance 45 filling said well and contacting and conforming to the wall surface thereof and bonding to that portion of said liftable flap member exposed through said opening, whereby when said liftable flap member is raised, said casting will separate from said flared opening to form a plug having a thickness in excess of the initial thickness of said full width closure flap, thereby providing a plug portion adapted to reenter said flared opening to provide a tight seal for said pouring opening.
